Milton H. Kreines

Application October 12, 1946, Serial No. 133,902

Term of patent 7 years

(Cl. D58—8)

To all whom it may concern:

Be it known that I, Raymond N. Sellon, a citizen of the United States, residing at Milwaukee, county of Milwaukee and State of Wisconsin, have invented a new, original, and ornamental Design for a Holder for a Bottle, of which the following is a specification, reference being had to the accompanying drawing, forming a part thereof, in which:

Figure 1 is a side elevational view, of a holder for a bottle, and

Figure 2 is a top plan view, showing my new design.

I claim:

The ornamental design for a holder for a bottle, as shown.

RAYMOND N. SELLON.
